UNITED STATES PATENT OFFICE.

EDWARD K. RABEY, OF DEANES, VIRGINIA.

SPRING-WHEEL.

1,172,224.

Specification of Letters Patent. Patented Feb. 15, 1916.

Application filed June 14, 1915. Serial No. 34,109.

To all whom it may concern:

Be it known that I, EDWARD K. RABEY, a citizen of the United States, residing at Deanes, in the county of Nansemond and 5 State of Virginia, have invented certain new and useful Improvements in Spring-Wheels; and I do hereby declare the following to be a full, clear, and exact description of the invention, such as will enable others skilled in the art to which it 10 appertains to make and use the same.

My present invention relates to improvements in a resilient outer structure for vehicle wheels, and is especially intended to 15 provide a resilient metallic construction which will give the desired cushioning effect as the vehicle travels over the road; yet will be strong, durable and efficient, not likely to become clogged up with mud, ice, 20 or other foreign matter, not likely to rattle, and not likely to get out of order.

My invention comprises a small inner wheel or hub, and a series of bent springs connected to the periphery thereof, the ends 25 of which springs are substantially straight, but when applied to the wheel are bent to form the arcs of circles, which ends are secured together to form a rim or tread, which tread may engage directly on the ground, 30 or may be supplemented by an exterior tread if desired.

My invention will be understood by reference to the accompanying drawings, in which one embodiment of the invention is 35 shown.

Figure 1 shows a side elevation of the complete wheel, parts being broken away; Fig. 2 is a section along the line 2—2 of Fig. 1, and looking in the direction of the 40 arrows; Fig. 3 is a detail showing in perspective one of the springs used in the construction of the wheel; and Fig. 4 shows a section through one of the safety buffers mounted in said springs.

45 A represents the hub of the wheel provided with suitable spokes B and a felly C on which the felly band D is mounted in the usual way.

Mounted on the felly band D is the chan- 50 neled rim E to which the inner ends of the

spring members F are secured as by means of suitable rivets. These spring members F are provided at their inner ends with one or two flanged portions 1 and 2, as shown most clearly in Fig. 3, and then project outward radially, as at 3, and are then bent in the form of a resilient loop 4, perforated as at 5 to receive the bolts H, and beyond this looped portion 4 the spring projects radially again terminating in the elongated 60 arm 7, which is normally straight, as indicated in Fig. 3, and when fitted on the wheel is bent to form the arc of a circle as indicated in dotted lines in Fig. 3, and as shown in full lines in Fig. 1.

The ends of the spring members F overlap as shown in Figs. 1 and 2, and these overlapping ends are fastened together securely as by rivets 9. Passing through the loops 4 of the spring members F, I provide 70 bolts H having heads h engaging the inner portion of said loops and reduced portions h' terminating in shoulders h² adapted to engage the inner edge of the buffers G. These buffers are preferably made of rubber, or other suitable elastic material, perforated as at g; and if made of rubber are preferably reinforced against wear by the washers g', bearing against the shoulder h² of the bolt H. Outside of the loop 4 the 80 outer ends of these bolts H carry steadyng springs I, engaging between the loops and the nuts H' which nuts engage the screw-threaded ends h³ of the bolts H, as shown most clearly in Fig. 4. Any suitable nut 85 lock arrangement may be used in connection with these nuts. The function of these buffers is to absorb the shock when an unusual or abnormal shock is thrown upon the wheel, such as when the vehicle is heavily 90 loaded, or when running over a stone or other obstruction in the road. By having the portions 3 and 6 of the spring members F radially disposed away from the outer rim and from the inner wheel or hub, there 95 will be little tendency of mud, snow, ice or the like clogging up the wheel and preventing the springs from functioning properly, and the rapid rotation of the wheel will normally clear itself of objectionable for- 100

5 eign matter. In the same way, the buffer arrangement is not apt to collect objectionable foreign matter to such an extent as to prevent the free and efficient operation of the buffers.

10 The size and resiliency of the springs would be determined by the load to be supported by the wheel, and would vary greatly according to the nature of the vehicle for which the wheel is intended. Thus, if the wheel is intended for use with an ordinary bicycle the springs would be very light and of high resiliency; while if it is intended for use with a wagon carrying 15 heavy loads the springs would be very much heavier and stronger.

20 In mounting the springs after the buffering arrangement is connected, the tension of the loops 4 is adjusted by screwing down the nuts H', causing the springs I to bear down on the loops and compressing the loops somewhat and putting the same under initial compression. Moreover, the bending 25 of the overlapping ends 7 of the spring members F will tend to put the metal tread of the wheel under initial compression, resisting any tendency to further compress the rim of the wheel. It will be seen that 30 all of the springs are under more or less compression, and are, therefore, what is commonly known as "live springs."

35 While I have shown rubber buffers G mounted in the loops 4, and adapted to prevent the undue compression of said loops when the load on the wheel exceeds a predetermined limit, it will be obvious that any other suitable form of shock absorber may be adopted for such purpose.

40 The wheel would ordinarily be used with its tread uncovered, as shown in Fig. 1, but if desired an outer band or rim of any suitable flexible material may be applied, or any suitable anti-skidding device may be mounted over the rim of the wheel. Such outer 45 rims, anti-skidding devices, etc., are not, however, part of my invention, and these may be varied at will to suit varying conditions of the road, the weather, etc.

50 It will be obvious that various modifications might be made in the herein described device, and in the construction, combination and arrangement of parts which could be used without departing from the spirit of my invention.

55 Having thus described my invention what I claim and desire to secure by Letters Patent of the United States is:—

60 1. In a resilient wheel the combination with an inner wheel or hub provided with a fixed metal band mounted thereon, of a resilient outer portion secured to said band and comprising a series of spring members projecting radially from said band, and having the central part of said radial portions

65 curved to form U-shaped loops, and the elongated outer ends of said spring members overlapping and secured together, and bent to form a resilient metal tread for the wheel, with buffers mounted in said loops, substantially as described.

70 2. In a resilient wheel the combination with an inner wheel or hub provided with a fixed metal band mounted thereon, of a resilient outer portion secured to said band and comprising a series of spring members projecting radially from said band, and having the central part of said radial portions 75 curved to form U-shaped loops, and the elongated outer ends of said spring members overlapping and secured together, and bent 80 to form a resilient metal tread for the wheel, with bolts spanning said loops and passing through perforations in said spring members, and buffers mounted on said bolts, and adapted to take up the shock when said 85 loops are compressed, substantially as described.

90 3. In a resilient wheel the combination with an inner wheel or hub provided with a fixed metal band mounted thereon, of a resilient outer portion secured to said band and comprising a series of spring members projecting radially from said band, and having the central part of said radial portions 95 curved to form U-shaped loops, and the elongated outer ends of said spring members bent at right angles to said radial portions and overlapping and riveted together, to form a resilient metal tread for the wheel, with buffers mounted in said loops, substantially as described.

100 4. In a resilient wheel the combination with an inner wheel or hub provided with a fixed metal band mounted thereon, of a resilient outer portion secured to said band and comprising a series of spring members projecting radially from said band, and having said radial portions curved to form loops, and the elongated outer ends of said spring members bent at right angles to said 105 radial portions and overlapping and riveted together, to form a resilient metal tread for the wheel, with bolts spanning said loops and passing through perforations in said spring members, springs and nuts on the outer ends of said bolts adapted to hold said loops under initial compression, and buffers mounted on said bolts, and adapted to take up the shock when said loops are compressed, substantially as described.

110 5. In a resilient wheel the combination with an inner wheel or hub provided with a fixed metal band mounted thereon, of a resilient outer portion secured to said band and comprising a series of spring members 115 projecting radially from said band, and having said radial portions curved to form loops, and the elongated outer ends of said spring 120

members bent at right angles to said radial portions and overlapping and riveted together, to form a resilient metal tread for the wheel, with bolts spanning said loops 5 and passing through perforations in said spring members, springs and nuts on the outer ends of said bolts adapted to hold said loops under initial compression, and rubber

buffers provided with wear plates mounted on said bolts, and adapted to take up the 10 shock when said loops are compressed, substantially as described.

In testimony whereof, I affix my signature.

EDWARD K. RABEY.
